Primary Examiner — Mary Ann Calabrese*Assistant Examiner* — Catherine Ho(74) Attorney, Agent, or Firm — Grants Law Firm; Ahan
Grant(57) CLAIM

I claim the ornamental design for a shelf tag, as shown and as described.

DESCRIPTION

FIG. 1 is a perspective view of the shelf tag, showing my new design;

FIG. 2 is the front view of the thereof;

FIG. 3 is a back view of the thereof;

FIG. 4 is a side view of the thereof;

FIG. 5 is the other side view of the thereof;

FIG. 6 is a top view of the thereof;

FIG. 7 is bottom view of the thereof; and,

FIG. 8 is a perspective view of the shelf tag shown in an environment of use.

The store shelf and goods are shown in broken lines for illustrative purposes only to show the environment and do not form part of the claimed design.
